2 SHEETS—SHEET 2.

UNITED STATES PATENT OFFICE.

WILLIAM B. CROSSLAND, OF PHILADELPHIA, PENNSYLVANIA.

WINDOW REFRIGERATOR.

1,410,378.

Specification of Letters Patent. Patented Mar. 21, 1922.

Application filed December 3, 1920. Serial No. 428,028.

To all whom it may concern:

Be it known that I, WILLIAM B. CROSSLAND, a citizen of the United States, residing at Philadelphia, in the county of Philadelphia and State of Pennsylvania, have invented a new and useful Improvement in Window Refrigerators, of which the following is a specification.

This invention relates to window refrigerators.

One object of the invention is to provide a refrigerator of this type, which is supported upon the window sill and may be held in various adjusted positions so that it may project into the room or out of the window, as desired.

Another object is to provide a cabinet capable of being used as a refrigerator and also as a case of shelves, capable of being supported upon the wall and providing a convenient storage receptacle.

Other objects are to provide a window refrigerator which has an exceptionally good circulation of air, which is light and easy to handle, and which exactly fits the lower window frame, making it weather tight.

A still further object is to provide an improved locking means for a receptacle adapted to be used as a window refrigerator.

The invention will be best understood from a consideration of the following detailed description taken in connection with the accompanying drawing forming part of this specification, with the understanding, however, that the invention is not confined to any strict conformity with the showing in the drawing, but may be changed and modified so long as such changes and modifications mark no material departure from the salient features of the invention as expressed in the appended claims.

In the drawing:

Figure 1 is a perspective view of a portion of a window showing a refrigerator constructed in accordance with the present invention projecting into the room;

Fig. 2 is a horizontal section of the same;

Fig. 3 is a vertical section;

Fig. 4 is a side elevation of the refrigerator showing it projecting out of the window;

Fig. 5 is a fragmentary elevation showing the refrigerator suspended from a hanger

when it is to be used as a cabinet or for merely storage purposes;

Fig. 6 is a detail horizontal section showing a portion of the locking means employed to adjustably hold the refrigerator;

Fig. 7 is a detail vertical section showing one of the locking fingers employed to hold the refrigerator;

Fig. 8 is a perspective view of one of the arrow shaped lugs used in the locking means of Fig. 6.

The numeral 10 designates the window sill and 11 the window jamb. The sash slides are indicated at 12. The lower and inner sash 14 and the upper and outer sash 15 are also illustrated. The main body of the refrigerator comprises a box or receptacle which is entirely open on one side, hereafter referred to as the front of the receptacle. The box has end walls 16, a top 17, a bottom 18 and a back 19. Upon the back a plurality of blocks 20 are secured near the bottom of the box. Near the top of the rear wall 19 a passageway 21 is provided, which passageway is covered by a perforated plate 22. A weather shield 23 is secured to the rear wall 19 and depends from a point near the top of the same extending below the passageway 21, but spaced a suitable distance therefrom. Thus a circulation of air through the box from the front to the rear is permitted whatever the location of the box. Two or more hooks 24 are secured upon the rear wall so as to permit suspension of the box upon a hanger, when it is to be used as a storage cabinet. Handles 25 are mounted upon the end walls 16 within the receptacle and make adjustment of the box in various positions in a window a relatively easy operation.

The end walls 16 each have two or more elongated, vertically extending slots 26 adapted to receive locking fingers 27, mounted upon bolts 28 secured in the window jamb. The fingers 27 are hook like in form and are swingable into and out of the elongated slots 26 hooking against the bottom wall of the slot, as seen in Fig. 7. The fingers are flat and are designed to prevent movement of the refrigerator either into the room or out through the window. The window sill 10 supports the receptacle, while either or both of the sashes 14, 15 rest

against the top 17 of the receptacle to further aid in the securing of the refrigerator. The fingers 27 are held spaced slightly from the jambs 11, so as to prevent marring the woodwork when swung.

The bottom 18 of the receptacle is provided with a wide opening 29. This wide opening in conjunction with the open front of the refrigerator insures a thorough circulation of air. Especially is this true when the box is projected almost wholly outside of the window, as indicated in Fig. 4. When the box is in this position, warm air may pass out through the perforated plate 22 and cool air may enter the box through the opening 29. Covering this passageway is a bottom tray or shelf 30. This shelf may be made of heavy galvanized wire or may be constructed in any other convenient manner, and is, of course, removable and easily cleaned. This tray or shelf being open, does not materially interfere with the air circulation referred to.

Upon each wall 16, several flat resilient, metal strips 31 are secured, preferably at their mid points by rivets or bolts 32. The ends of the strip are separable from the walls 16 of the receptacle but are normally held by the resilience of the strip snugly against said wall. Near each end of each strip a perforation 35 is provided in the wall. A locking lug is mounted in any desirable way upon each strip 10, each locking lug including a rectangular shank 33 and an enlarged head 34, the head being arrow shaped. The arrow head 34 projects outwardly through the corresponding perforation 35 and when the refrigerator is in position in a window, engages with the walls of one of the sash slides 12. Since there are two of these slides and since the two ends of each strip 31 carry locking lugs, it is possible to hold the receptacle in four positions, with the locking lugs active. An angle bar 39 is secured upon the top 17 at the forward or front edge thereof in order to cooperate with the lower end of either window sash to prevent the box from falling out of the window when it is projected, as indicated in Fig. 4. Obviously the receptacle may be supported in such position that the angle bar 39 engages with the sash 15 whereupon the sash 14 may be closed over the front of the box, thus providing a glass closure therefor. It is only when the refrigerator projects into the room that the locking fingers 27 are used.

Removable shelves 36 are provided, there being as many shelves as there are opposite strips 31. These shelves are supported upon the rectangular blocks or shanks 33 of the locking lugs. Each shelf preferably will comprise a rectangular frame and a screen of reticulated material. When the shelves are in position, it will be clear that the strips 31

may not be swung away from the wall 16, but on the contrary are held against such movement. It is only when the shelves 36 are taken out that the locking lugs may be adjustably engaged with the sash slides. The locking of the receptacle with the window frame is thus seen to be a secure one.

If the outside temperature is warmer than the room temperature, the refrigerator may be taken out of the window and suspended upon a wall. In such a case the hanger rod 38 may be employed which is secured to a wall 40 by screw eyes 37. The hooks 24 will be engaged over the rod 38 and the blocks 20 will space the receptacle from the wall. When so used the receptacle provides a convenient storage space for foods. If desired, the box may be provided with its own closure so that the sash need not be depended upon.

The features of this refrigerator are its lightness and portability; the ease with which it is adjusted; the security with which it is locked in position; and the thorough air circulation which is induced. The construction is very simple and yet the box, in cold weather at least, serves the purposes of an expensive refrigerator, while representing an outlay of an inconsiderable sum for first cost. It is most economical to place foods warm from the table in such a window refrigerator as this, and only after they have cooled down place them in an ice refrigerator. Thus considerable waste of ice is avoided.

What is claimed is:—

1. In a window refrigerator, a receptacle adapted to rest on the window sill, a resilient strip mounted on the end wall of the receptacle within the same, a perforation in said wall at one end of said strip, and holding means mounted on the strip and passing through said perforation for engagement with the sash slide to hold the receptacle against displacement.

2. In a window refrigerator, a receptacle adapted to rest on the window sill, a resilient strip mounted on the end wall of the receptacle within the same, a perforation in said wall at one end of said strip, a shelf within the receptacle, and means mounted on the strip and passing through said perforation for engagement with the sash slide to hold the receptacle against displacement, said means also providing a support for the shelf.

3. In a window refrigerator, a receptacle adapted to rest on the window sill, a resilient strip secured at a mid point to the end wall of the receptacle within the same, perforations in said wall at each end of said strip, means secured to the ends of the strip and normally projecting through the corresponding perforation for engagement with the sash slide to hold the receptacle against displacement, and a shelf supported upon

said means and holding said strip against inward movement whereby said shelf must be taken out of the receptacle before the strips, and therefore before the receptacle, 5 can be moved.

4. In a window refrigerator, a receptacle adapted to rest on the window sill, a resilient strip secured at a mid point on the end wall of the receptacle within the same, 10 perforations provided in said end wall at each end of said strip, locking lugs mounted upon each end of the strip and adapted to engage with the sash slide to hold the receptacle against displacement, said locking 15 lugs comprising a pointed head and a shank of reduced size relative to said head, said head projecting through the perforation and said shank projecting inwardly of the receptacle, and a shelf supported upon the 20 shank and holding said strip against movement whereby the receptacle may only be moved after the shelf has been lifted out of engagement with said strip.

5. In a window refrigerator, a receptacle 25 adapted to rest on the window sill, said receptacle including end walls, a rear wall and an open bottom and front, ventilation means provided in said back wall near the top thereof, the bottom being open to the 30 passage of air currents, locking means for engagement with the window frame, and removable trays or shelves mounted within the receptacle engaging with said locking means to prevent movement thereof.

35 6. In a window refrigerator, a receptacle adapted to rest on the window sill, said receptacle comprising a substantially rectangular box having an open front, a rear wall provided with ventilation means, a bottom 40 provided with ventilation means, a plurality of shelves supported within the box, locking means mounted upon the receptacle and engageable with the window frame for holding the box in various adjusted positions relative to said frame, said shelves 45 being supported upon said locking means

and in turn preventing movement of the locking means out of engagement with the window frame as long as the shelves are in position, and other locking means 50 mounted on the window jamb and entering the receptacle to prevent displacement thereof.

7. In combination with a receptacle comprising a substantially rectangular box, a plurality of shelves supported within the box, and locking means mounted upon the receptacle and projecting from the sides thereof, said shelves being supported by 55 said locking means to maintain the same 60 in locking engagement.

8. In a window refrigerator, a receptacle adapted to rest on the window sill, said receptacle comprising a substantially rectangular box, a plurality of shelves supported 65 within the box, locking means mounted upon the receptacle and engageable with the window frame for holding the box in various adjusted positions relative to said frame, said shelves being supported upon 70 said locking means and in turn preventing movement of the locking means out of engagement with the window frame as long as the shelves are in position.

9. In a window refrigerator, a receptacle 75 adapted to rest on the window sill, a resilient strip secured at a mid point on the end wall of the receptacle within the same, perforations provided in said end wall at each end of said strip, locking lugs mounted 80 upon each end of the strip and adapted to engage with the sash slide to hold the receptacle against displacement, said locking lugs comprising a pointed head and a shank of reduced size relative to said head, said 85 head projecting through the perforation and said shank projecting inwardly of the receptacle.

In testimony, that I claim the foregoing as my own, I have hereto affixed my 90 signature.

WILLIAM B. CROSSLAND.
